ABSTRACT: The invention relates to an oil-pump assembly which includes a pressure-regulating valve. The object of the invention is to remove air and oil from the spring chamber of the pressure-regulating valve. The shaft seal chamber has a slide-ring seal attached to the pump shaft which operates as a check valve. The pump casing is formed so that the shaft seal chamber has fluid communication with the shaft bore, the suction inlet of the pump and the spring chamber of the regulating valve. The shaft seal functions as a check valve which opens when pressurized oil from the pump discharge flows outwardly through the shaft bore. The mouth of the passage leading to the spring chamber of the pressure-regulating valve is opened or closed depending on the axial position of the shaft seal and when the mouth is open, air and oil is drawn from the regulating valve spring chamber to the suction inlet of the pump through the shaft seal chamber.

**OIL-PUMP WITH A PRESSURE-REGULATING VALVE
CONNECTED ON THE OUTLET SIDE**

The invention relates to an oil-pump with a pressure-regulating valve connected on the outlet side and a shaft seal in the form of a slide-ring seal, and in which a backing member, rotatable with the shaft, bears resiliently against an inner end wall of the housing, and leakage oil is passed along the shaft and through the gap between the backing member and the end wall into a housing chamber containing the slide ring, a chamber in the pressure-regulating valve being in communication with the suction side of the pump by way of a path containing a check valve, which path passes through the housing chamber.

Pressure-regulating valve must normally have a connection with the suction side so that oil that penetrates into zones where it is not required during operation can be discharged therefrom. This applies particularly in the case of the chamber behind the control piston, since oil that collects there would adversely affect the performance of the pressure-regulating valve. On the other hand, however, this chamber can easily become filled with air during the standstill periods, since the movable seals provided for the oil offer only slight resistance to the air. If, when the pump starts up, this air is passed to the suction side, the pump delivers air, at least in part, instead of oil, and the necessary oil pressure can only be built up slowly if at all. In the extreme case, the oil-pump circulates only air through the pressure-regulating valve; it then functions to some extent in short circuit.

To remedy this defect, an arrangement has been proposed in which the stated chamber in the pressure-regulating valve communicates, by way of a passage, with the housing chamber for the slide-ring seal, and this communicates with the suction side of the pump by way of a check valve which only opens when a predetermined pressure differential occurs. Since such pressure differential can only occur if the pump has delivered a sufficient quantity of oil, the air contained in the pressure-regulating valve does not interfere with the starting-up process.

There are of course difficulties in designing the check valve to function correctly. On the one hand a large closing pressure and therefore a strong valve spring are required in order to close the check valve tightly in all conditions and also to provide an effective check to the air. On the other hand, the force required for opening must not be too great and the valve spring should not therefore be too strong, since the pressure permissible in the housing chamber is limited on account of the tightness of the pump.

The object of the invention is to design an oil-pump of the simplest possible construction in such a way that, on the one hand, the check valve can be kept closed by an adequate closing pressure, while on the other hand impermissibly high-pressure levels do not occur in the housing chamber.

According to the invention this object is achieved by causing the backing member, displaceable when leakage oil occurs, to control the check valve.

Leakage oil only occurs to any appreciable extent if the pump generates a considerable pressure, i.e. when it delivers oil, in the main, and no air. The leakage oil acts over a relatively large area of the backing member and therefore applies considerable forces to this member. These forces are so great that they are able to influence the relatively strong spring of the slide-ring seal. If therefore, in accordance with the invention, this backing member is used for controlling the check valve, sufficiently great forces are available for the opening operation; the check valve can therefore be kept closed with a large closing force. Moreover, this control arrangement becomes automatically effective only when the pump is running at speed and is delivering sufficient oil. The pressure in the housing chamber can nevertheless be kept at any level, even a low level if required, since this chamber can communicate directly with the suction side or a point of definite pressure in the pump, e.g. with a certain chamber defined by teeth.

Here, it is particularly advantageous if the backing member is firmly connected to the closure member of the check valve.

In this case, the spring of the slide-ring seal simultaneously acts as a valve spring, so that its relatively great force can be used as the closing force.

Furthermore, it is also advantageous if the sealing surface of the check valve is formed between the backing member and the end face. The backing member then forms the closure element of the check valve and the inner end face of the housing constitutes the valve seat. In this manner a check valve having good functional properties is obtained by using components already present.

In a preferred embodiment, the passage leading from the pressure-regulating valve to the housing chamber terminates in the path of the leakage oil in the direct vicinity of the backing member. At this point, the pressure of the leakage oil has already relaxed to a large extent, so that a lower pressure obtains, as required, in the adjoining chamber of the pressure-regulating valve.

The invention will now be described in more detail by reference to an embodiment illustrated in the drawing, in which:

FIG. 1 shows the connection diagram of a pump that can be equipped in the manner proposed by the invention, and

FIG. 2 is a longitudinal section through an embodiment of the invention, the passages of importance to the invention being turned to bring them into the plane of the section.

Referring to the diagram seen in FIG. 1, an oil-pump 1 draws oil from a sump 3 by way of a suction pipe 2 and delivers it through a pressure pipe 4 to a pressure-regulating valve 5 and, through a nozzle pipe 6 to a fuel-oil nozzle 7. The pump is powered by a single-phase asynchronous motor 8 through a shaft 9, which extends through a sealing device 10 incorporating a slide-ring seal. The pressure-regulating valve 5, illustrated in a much simplified manner in the drawing, has a piston 11, which in the at-rest position blocks the inlets to the nozzle pipe 6. When the pressure in the pressure pipe 4 rises, the piston 11 is displaced, overcoming the pressure of a spring 13, adjustable by means of a set screw 12, and an edge 14 of the piston thereby uncovers an orifice 15 to a greater or lesser extent. Consequently, surplus oil flows through a section 16 of the pipe. The chamber 17 behind the piston is connected by a pipe 18 to the pipe 16. The pipe 16 leads to the interior of the sealing arrangement 10 by way of a check valve, not illustrated in FIG. 1. From this sealing arrangement, a return pipe 19 leads, on the one hand, through a section 20 to the suction pipe, and, on the other hand, through a section 21 to the sump. The parts contained in the rectangle 22, shown in broken lines, are accommodated in a common housing which is represented by the housing 30 and cover 31 of the unit shown in FIG. 2.

In the form of construction shown in FIG. 2, the pump has an inner toothed wheel 23, which is firmly connected to a shaft 24 (corresponding to shaft 9 in FIG. 1) so as to rotate therewith, and an internally toothed ring 25, which is able to rotate in the fixed housing 26. The parts 23, 25 and 26 are covered by an end-plate 27, in which are provided distributing grooves etc. The parts 23, 25, 26 and 27 which correspond to the pump 1 of FIG. 1, are held on the end-face 29 with the help of screws 28. This pump arrangement is covered by its own cover 31, which surrounds a suction chamber 32. Contained in this suction chamber is a screen 33, one edge of which engages in an annular groove 34 in the end-face 29 of the housing, and the other edge of which extends into a seal 35, which is formed on the circumference of a resilient disc 36. The space 37 between the disc 36 and the cover 31 is filled with air and acts as a shock-absorber. The suction chamber 32 is connected by way of passages, not illustrated, to a port, to which is connected section 2 of the suction pipe of FIG. 1.

The shaft 24 is mounted in two bearing bushes 38, which are fitted in a longitudinal bore in the housing 30. At that side opposite the end-face 29, the housing 30 contains a chamber 39 which accommodates a slide-ring seal which corresponds to the sealing device 10 of FIG. 1. The slide-ring seal comprises a slide-ring 40, rotating with the shaft, and a fixed face-ring 41.

The latter is held in position by means of a circlip 42 and is pressed by a corrugated spring 43 against an annular surface 45 on the end face of the chamber 39, an O-ring 44 being thereby compressed. Mounted on the shaft 24 to rotate therewith is a backing member 46 which serves to support a spring 47, which applies an axial pressure on the slide-ring 40 by way of a washer 48. The slide-ring is also coupled, by way of the spring 47 and fingers on the washer 48, with the backing member 46 to give a rotary drive. When the equipment is in operation, a floating bearing is formed between the inner end-face 49 of the housing and the backing member 46, since leakage oil emerges from the pump and flows along the shaft 24 which corresponds to the shaft 24' of FIG. 1, into the chamber 39. For this purpose, axial grooves can be provided in the bearing bushes 38 or in the bore of the housing in which they are accommodated, as shown in broken lines on the exterior of the bearing bush at 50, and on the interior of the bearing bush at 51.

The housing also contains a bore 52 which accommodates the moving parts of a pressure-regulating and cut-off valve, which is the valve assembly 5 of FIG. 1. From this bore 52 runs a passage 53, at the correct functional level of course, and this passage, which corresponds to the pipe 16 of FIG. 1, terminates at the point 54 near the end of the leakage oil path, in this instance therefore at the end of the longitudinal bore in the housing 30. A further passage 55 which corresponds to the pipe 19 of FIG. 1, leads from the housing chamber 39 to the annular groove 34 in the suction chamber 32.

When a pump of this kind is set in operation, if there is direct communication between the bore 52 and the suction chamber 32, there would arise the danger that the pump, instead of delivering oil and building up a pressure, would suck air from the bore 52 and, due to the low resistance to air in the pressure-regulating valve would deliver in that direction again.

by short circuit so to speak. In the present case such direct communication is not possible, since the backing member 46, acted upon by the pressure from the strong spring 47 and bearing against the end-face 49, acts as a check valve. However, as soon as the pump delivers oil and sets up a certain pressure, leakage oil passes outwards along the shaft 24 and, as soon as it reaches a certain pressure, removes the backing member 46 from the end-face 49. Thus, not only is a floating bearing created, but also a passage for the medium to be discharged from the bore 52 i.e. oil primarily but initially air as well.

We claim:

1. An oil-pump assembly comprising a casing, a suction inlet chamber, a pressure-regulating valve having a spring chamber, 15 a shaft bore in said casing, a pump shaft rotatably journaled in said shaft bore, said casing having a shaft seal chamber adjoining said shaft bore, said shaft seal chamber having a wall with a sealing seat formed thereon, a slide-ring seal in said shaft seal chamber including resilient means axially biasing said seal against said seat, said casing having first passage means between said valve spring chamber and said shaft seal chamber, said passage means having a mouth within the confines of said seat so that the egress of fluid from said passage means to said shaft seal chamber is controlled by said slide-ring seal, said casing having second passage means between said shaft seal chamber and said oil pump suction inlet chamber.

2. An oil-pump pump assembly according to claim 1 wherein said slide-ring seal includes a backing member attached to said shaft for rotation therewith and axial movement relative thereto.

3. An oil-pump assembly according to claim 2 wherein said spring chamber is formed in said casing.
